UNITED STATES PATENT OFFICE.

FRANK HOKE, GEORGE H. ROSSEBO, AND EDWARD E. COLLISON, OF INDIANAPOLIS, INDIANA.

DESIGN FOR A COUNTER.

Application filed August 18, 1927. Serial No. 23,143. Term of patent 3½ years.

To all whom it may concern:

Be it known that we, FRANK HOKE, GEORGE H. ROSSEBO, and EDWARD E. COLLISON, citizens of the United States, residing at Indianapolis, in the county of Marion and State of Indiana, have invented a new, original, and ornamental Design for a Counter, of which the following is a specification, reference being had to the accompanying drawing, forming a part thereof.

In the drawings Fig. 1 is a perspective view of the article looking at the rear, and

Fig. 2 is a perspective view looking at the front.

We claim:

The ornamental design for a counter as shown.

In witness whereof, we have hereunto set our hands at Indianapolis, Indiana, this 10th day of August, A. D. one thousand nine hundred and twenty-seven.

FRANK HOKE.
GEORGE H. ROSSEBO.
EDWARD E. COLLISON.
